Primary Examiner — Michael C Stout*Assistant Examiner* — Katelin G Kloberg*(74) Attorney, Agent, or Firm* — Cook Alex Ltd.(57) CLAIM

The ornamental design for a table, as shown and described.

DESCRIPTION

FIG. 1 is a perspective view of the table;

FIG. 2 is a front elevational view thereof, the rear, left side and right side of which are identical;

FIG. 3 is a top plan view thereof; and,

FIG. 4 is a bottom plan view thereof.

The broken line portions of the drawings are included to show portions of the article that form no part of the claimed design and represent environmental structure only.

1 Claim, 4 Drawing Sheets(56)
